UNITED STATES PATENT OFFICE.

DAVID RENSHAW, OF BRAINTREE, MASSACHUSETTS.

UTILIZING THE EXHAUST OF ENGINES.

SPECIFICATION forming part of Letters Patent No. 298,119, dated May 6, 1884.

Application filed February 21, 1883. Renewed October 10, 1883. (No model.)

To all whom it may concern:

Be it known that I, DAVID RENSHAW, of Braintree, in the county of Norfolk and State of Massachusetts, have invented certain new and useful Improvements in the Process of Utilizing the Exhaust of Engines; and I do hereby declare that the following is a full, clear, and exact description of the invention, which will enable others skilled in the art to 10 which it appertains to make and use the same, reference being had to the accompanying drawing, and to the letters of reference marked thereon, which form part of this specification.

The object of this invention is the utilization of the exhaust of engines, and consequent saving of the greater portion of the heat now lost in the working of engines.

It consists, first, in producing and maintaining in a superheater a greater pressure than its source of supply, (which in this case is the working boiler or reservoir.) This is done by devices shown in application Serial No. 86,129. This highly-heated steam, of greater pressure than the working boiler, is 20 then conducted to an injector located between the superheater and boiler, and then brought in contact with the exhaust, and also with water taken from the boiler, said water being delivered to the injector under boiler pressure 25 and temperature, or under the boiler-pressure and partially cooled, or under atmospheric pressure, cooled or not, as desired, the effect of which is the return of all of the steam and water to the boiler from which they were taken.

30 The accompanying drawing shows a side elevation of one method of illustrating my invention, the superheater being in section, and embodies some of the features shown in application Serial No. 86,223.

35 A is the boiler or vessel. B is the live-steam injector, and C the exhaust-steam injector—the former for supplying the superheater, and the latter for forcing the combined mixture into the supply-boiler.

40 D is the atmospheric cooling-tank, and E the cooling-vessel under boiler-pressure. F is the superheater, and Y its temporary water-supply tank.

45 The connecting-pipes and valves will be alluded to and their function pointed out in the

description setting forth the operation of the apparatus.

The operation is as follows: A sufficient quantity of water, by opening valve x, is allowed to pass from tank Y to the superheater, 55 which, when turned into steam and highly superheated, will give a pressure as much greater as may be desired than the working pressure raised on boiler A. The valve x is then closed. The superheater having attained the desired pressure, valves S and m are opened, which allows water to pass from the boiler A at the temperature and pressure due to it into and through the injector B. Valves w w are at the same time opened, which allows 60 steam to pass from boiler A, through pipe n, to and through injector B, and also allows a portion of the highly-superheated steam of greater pressure than the boiler A to pass into pipe h, and through the injector B, whereby 65 the higher pressure is maintained on said superheater, while a portion of the steam superheated in it is passing through pipe e to the injector C, for the purpose of forcing the exhaust through it and back into the boiler A, 70 from which it was taken, the exhaust passing from the engine to the injector C through pipe d.

The water used in working injectors C and B passes from boiler A through pipes b and 80 l; or the injectors C and B may be furnished with water at the boiler-pressure, but partially cooled, by closing valve S and opening valves q and r, allowing the boiler-water under pressure to pass through cooling-coil f, located in tank E, and from thence through pipes b and l to injectors B and C. Further, the water necessary for the working of injectors B and C may be furnished to them at atmospheric pressure. In such case the valves 85 S, q, and r will be closed and valve G on pipe g opened, allowing the boiler-water to pass into open tank D, from which it is carried to the injector C through pipe h, and to the injector B through pipe h, pipe l, and pipe b.

90 The arrangement of the parts may be differently located, as occasion and circumstances may require, as I lay no claim to the particular arrangement shown.

95 Having described my invention, what I claim is

as new, and desire to secure by Letters Patent, is—

1. The process herein described of utilizing the exhaust of engines by first injecting live steam with a small quantity of water into a superheater by means of the steam previously superheated in said superheater, thereby producing and maintaining a high pressure in the superheater, then injecting a portion of the boiler-water with the exhaust of the engine into the boiler by means of a subsidiary injector working under a superior pressure, as set forth.

2. The combination of means for utilizing the exhaust of engines, consisting of the boiler, the superheater, the primary injector, and the subsidiary injector, and the water-tank, with their intermediate connection, as described.

In testimony that I claim the foregoing as my own invention I affix my signature in presence of two witnesses.

DAVID RENSHAW.
